UNITED STATES PATENT OFFICE.

WALTER PARSONS, OF MEDFORD, MASSACHUSETTS.

PIE-PLATE.

SPECIFICATION forming part of Letters Patent No. 274,219, dated March 20, 1883.

Application filed February 9, 1883. (No model.)

To all whom it may concern:

Be it known that I, WALTER PARSONS, a citizen of the United States, residing at Medford, in the county of Middlesex and State of Massachusetts, have invented certain new and useful Improvements in Pie-Plates; and I do hereby declare that the same are fully described in the following specification, and illustrated in the accompanying drawings.

This invention relates to improvements in pie-plates; and it has for its object to prevent the juice or liquid part of pies from running over the edge and down the outside of the pie-plate during the process of baking the pies in ovens, for which purpose my invention is carried out as follows, reference being had to the accompanying drawings, where—

Figure 1 represents a plan view, and Fig. 2 a central longitudinal section, of my improved pie-plate. Figs. 3 and 4 represent in plan and longitudinal section a modification of my invention.

Similar letters refer to similar parts wherever they occur on the different parts of the drawings.

a represents the bottom of the pie-plate, and *a'* represents the curved side or rim, as shown in Figs. 2 and 4. Outside of the rim *a'*, I locate an annular groove or gutter, *a''*, which may be made in one piece with the rim *a'*, or secured to it by means of solder or other fastening medium, as represented in Figs. 1 and 2. Such groove may be made semicircular in section, or V-shaped, or of any other sectional shape, as may be desired; or said groove or gutter may be made separate from the rim of the pie-plate, so as to be detachable from the latter, if so required, as shown in Figs. 3 and 4, in which the annular groove or gutter *a''* is preferably provided with an annular flange, *a'''*, adapted to fit on the inside of the rim *a'* of the pie-plate, as shown in Fig. 4. The annular groove or gutter *a''* is adapted to receive the

overflow of the juice or liquid contents of the pie while being baked in the oven, thus preventing such part of the pie from running over the upper edge of the rim *a'* and down the outside of the latter. This my improved pie-plate may be made of metal, earthenware, or porcelain to equal advantage, and the annular groove or gutter *a''* may be made in one piece, or firmly attached to the pie-plate rim, or detachable from it, as may be desired. In making the invention from sheet metal I prefer to make the annular groove *a''* in one piece with the pie-plate *a a'*; but if the latter is made of porcelain or earthenware I may prefer to make the annular groove *a''* of metal, and detachable from the pie-plate, as shown in Figs. 3 and 4. Either construction and arrangement is practical, and answers the purpose for which I have intended it. By the use of such an overflow groove or gutter *a''* on the outside of the upper edge of the rim *a'* the unsightly and annoying overflow of the sticky juice or liquid part of the pie on the outside of the pie-plates is entirely obviated, and pie-plates of my improved construction may be taken from the oven and placed directly upon table-cloths without soiling the latter.

Having thus fully described the nature and construction of my invention, I wish to secure by Letters Patent, and claim—

The herein-described improvement in pie-plates, consisting of an annular groove or gutter, *a''*, located around the upper edge of the rim *a'*, and adapted to receive the juicy overflow of pies while being baked, in a manner as herein set forth.

In testimony whereof I have affixed my signature in presence of two witnesses.

WALTER PARSONS.
